UNITED STATES PATENT OFFICE.

JOHN CHALLONER AND JOHN W. CHALLONER, OF OMRO, WISCONSIN.

SHINGLE-SAWING MACHINE.

SPECIFICATION forming part of Letters Patent No. 296,525, dated April 8, 1884.

Application filed March 17, 1883. (No model.)

To all whom it may concern:

Be it known that we, JOHN CHALLONER and JOHN WM. CHALLONER, of Omro, in the county of Winnebago and in the State of Wisconsin, 5 have invented certain new and useful Improvements in Shingle-Machines; and we do hereby declare that the following is a full, clear, and exact description thereof.

Our invention relates to machines for the manufacture of shingles; and it consists in a machine which is adapted to saw shingles from the spalt as well as from the block, thus utilizing what has heretofore been a waste product, all as will be more fully set forth hereinafter.

In the drawings, Figure 1 is a front elevation, Fig. 2 is a side elevation, and Fig. 3 a top view, of our machine adjusted for sawing shingles from the block. Fig. 4 is a top view 20 of the machine with the spalt-frame in place. Figs. 5 and 6 are details of the tipping-table supports, and Figs. 7 to 10 are views of the spalt-frame and its details.

A is the main frame of the machine, and is 25 made, preferably, of angle-iron. The front of this frame (shown in Fig. 1) extends inward at the center, as shown at A', to afford room for the swinging supports of the tipping table, while the flat top of the angle-iron of said 30 frame forms a shelf or bearing, A², for the stationary supports of said table, the said support being shown in detail in Figs. 5 and 6.

B is a leveling-bar, with central hub, B', having a transverse perforation, b', and an 35 end housing, B², with perforation b² for containing a spring, B³. There are also three front projecting lugs, B⁴ B⁵ B⁶, each with a screw-threaded perforation and two rear lugs, B⁷ B⁸, one at each end, each provided with 40 two screw-threaded holes.

C is a swinging frame of general T shape, the top of which is cut away at the center at c, and this cut-away part admits the hub B' of the leveling-bar, and then a bolt, c', is passed 45 through holes c² c³ in the swinging frame and the hole b' in the hub, and the frame C is suspended from the bolt in the hub. This frame C has a front recess, C', and a second recess, C', back of this.

C² is a securing-plate bolted to the lower 50 part of the stem of the T-frame C, and the leg

or standard D of the tipping table rests in the recess C'; and is held in place by the plate C³ and its attachments, to be hereinafter described.

The leveling-bar B is secured in place in the following manner: Adjusting-screws b⁴ b⁷ at one end and b⁸ at the other end are passed down from the top of the bar through the holes in the lugs, the screws b⁴ and b⁸ resting on the 60 shelf A² of the main frame, while the screw b⁷ rests on a lug or extension, a², of the said shelf. When the proper adjustments have been made and the bar B is level to the work of the machine, it is secured in that position 65 by the binding-screws b⁹ b¹⁰, one at each end, passing through the shelf A² and the lugs B⁷ and B⁸, respectively.

The left wing of the T-frame C is bifurcated for the reception of a link, C¹, the end of which 70 is pivoted therein, while its other end is similarly pivoted between the forks of a bifurcated block, B¹, which slides in the housing B², and is governed by the spring B³, already named, while tension of said spring is regulated by a 75 block on the end of screw-bolt B¹⁰, which passes through a hole in the plate B¹¹ at the outer end of the said housing.

E is a hand-lever attached to one end of the T-frame C for tipping it, and F is a similar 80 lever for automatically tipping the said frame and its attachments, as will be described further on.

The tipping table already alluded to consists of the standard D and H-shaped top D', 85 from which rise the rails D² D³. The standard, as stated, rests in a recess in the swinging frame C, and is secured in place by plate C'. From the base of this plate projects inwardly the lug c', which is perforated for the 90 reception of the vertical adjustment-screw c', carrying a jam-nut, while another screw, c⁵, extends horizontally through the face of the plate C', and also carries a jam-nut, so that when the standard has been raised to the 95 proper height it can be held rigidly in such position by means of the screw c' and nut just named.

The main frame A rises to some height above the plane of the front central shelf, A², 100 at each side, and upon the top of this frame an auxiliary frame, A³, rests, and is securely

bolted thereto. This latter frame serves as a support for the head-blocks G G, which sustain the guides of the carriage, the base of said blocks being provided with shoulders *a* for lateral adjustment, moving in correspondingly-shaped ways in bracket-extensions *a*³ of the auxiliary frame A³. Midway between these brackets *a*³, on each side of the auxiliary frame, are the slotted flanges *a'*, to receive the bolts 5 G', which extend down through the head-blocks G, in order to secure the latter in place when they have been laterally adjusted in or out, as required.

To the inside of each head-block, at each 15 end, are pivoted bell-cranks H H and H' H', the latter being near the front of the machine, and having their vertical arms extended up into the levers H², the top of said levers being bifurcated, and having pivoted between their 20 forks the tops of the depending pawls H³, which are kept in mesh by the springs h² with the teeth on the segments I. The vertical arms of the bell-cranks are connected together by the links h, while their other arms are perforated for the reception of studs k on the 25 guides K. The segments I are provided with vertical slots, through which pass the bolts h', which also serve to secure the bell-cranks H' to the head-block G, and a perforated flange, 30 i, projects from each segment, through which depends an adjusting-screw, i², the point of which bears upon a collar, i', on the bolt h', between its nut i⁴ and the said segment, and by means of which the segment may be raised 35 or lowered. In order to still further secure the adjustment of the segment and prevent the same from being pulled out of position, the head-blocks G have vertical lugs g, with perforations in their upper ends through which 40 other adjusting-screws, i³, are passed to bear against the rear edges of the segment-standards, as shown, and the segments are secured, when adjusted, by means of the nut i⁴ on the end of the bolt h', already described.

45 The carriage for supporting and handling the block will now be described. This is constructed chiefly of pipe or tubing, to enable one part to telescope or slide within another, as well as to insure great lightness of construction.

50 L L are the front and rear parts, formed of pipes whose ends are screwed into the hollow T-shaped elbows L' L', and M M' are the side parts, also screwed into the elbows L' L'.

55 N N are rods, which slide within the parts L L and support the carriage from the guides K K, which they grasp with their forked outer ends, and which have oil cups or openings n n on top, so that oil, &c., can be there admitted 60 to lubricate the said guides, while the elbows L' have set-screws l to bear against the rods N, and secure all these parts rigidly together after they have been adjusted to the required relative positions.

65 O is the left-hand dog-frame, having ends which hook over the rods L, and are rigidly secured thereto, after adjustment, by set-screws

70 75 75 t', and which frame carries a continuous knife-edged dog, o, while O' is the right-hand dog-frame, whose front end simply rests on the front rod L, without attachment thereto, and which is provided with a bottom plate, which extends under the rear rod L, while its operative face is divided into a series of teeth, o' o', for the more ready attachment and detachment of the block.

M² is a loose sleeve on the rod M', and to this sleeve the standards m m are rigidly clamped, and between the plates of the forward standard is secured the shank of the 80 handle M³, while the standards m m are connected to the dog-frame O' by means of the links m' m'. The shank of the other handle, M⁴, is simply secured by set-screw to the rod M.

The means for automatically tipping the table D D' D² will next be described. The rear end of the right-hand guide K is fitted with a collar, k', against which a spring, K', bears, while between the other end of this spring and the forked ends of the rear rod N, and surrounding the guide K, is situated the sleeved end k² of the short arm of a bent rod, K², the forward end of which bears a pawl, k³, the operative end of which engages with the notches p in the outer rim of a trefoil-cam, P. The 90 said cam has a hollow grooved axle, P', which is sustained within a cup-bearing, P², bolted to the front end of the auxiliary frame A³, the said cup-bearing having interior projections, p', which fit within the groove on the exterior 100 of the axle P', and thus sustain it. The free end of the lever F, already named, extends through the hollow axle P and into the trefoil-cam, where it is forked or branched, and each fork carries a friction-roller, f, operated by 105 the described trefoil-cam. Now, when spalts are to be sawed up into shingles, the tipping table and its attachments are not used, and the dog-frames O and O' are pushed back to the 110 sides of the carriage, as shown in Fig. 4, and the supplementary or spalt frame takes their place. This frame consists, primarily, of the side timbers, Q Q', angle-plate end pieces, Q² Q², and at each corner it is furnished with the hooked plates q, with set-screws q' q², whereby 115 the frame can be suspended on the front and rear carriage-rod L L and secured thereto, as shown.

Q³ Q³ are additional longitudinal floor-beams, which are fastened rigidly to the angle-piece 120 Q², and between which are located the bars R R', which carry the dogs for the spalts.

S S are transverse frames bolted to the under side of the angle end pieces, Q², and with downward projections s s, carrying the dog-bars R R', which latter are arranged in pairs, as shown best in Fig. 8, so that the dogs r or r' in each adjacent bar point in opposite directions. The said bars (which are angle-shaped) are provided with end extensions, R², which contain diagonal slots r², extending in each bar in parallel direction with the dogs in said bar, and the said bars have also central vertical projections, R³ R⁴, which are 125 130

provided with perforations. The bars R have the projections R', and these have the holes r³ near their top, while the bars R' have the projections R', and these have the holes r⁴ near their base. The slotted ends R' of these dog-bars extend between the downward projections s of the transverse frames S, and are held in place by the bolts s', which pass through the projections s and through the said slots r², which slots are disposed in opposite directions, as indicated by full and dotted lines in Fig. 9. Each pair of dog-bars R R' is connected together in the center by means of the link T, Fig. 10, which has bottom perforations, t, and above this, slot t', the hole t affording means for bolt-connection with the bar R' through the hole r⁴ in its central projection, R', while the slot t' affords similar means of bolt-connection with the bar R through the hole r³ in its central projection, R³, while near the top of each link T there is another perforation, t², that connects with the horizontal links U, forming part of the actuating device of the said dog-bars. V V are standards bolted to the top of the beams Q³ Q³ near the front-ends, and to these standards are pivoted the arms W W of the handle w, while near the said standards V the arms W W are perforated to receive the bolts u, that connect the front ends of the links U, whose other ends are connected by the bolts u' to the links T, as already indicated.

X is the saw, supported horizontally at the rear of the machine on the upright shaft x, sustained, as shown, in suitable bearings; and Y is the pulley by which said shaft is actuated, and Z is the guard surrounding said saw.

The operation of our device is as follows: The parts being adjusted, say, as shown in Fig. 2, with the tipping table inclined to the left, the carriage is pulled forward by means of the handles M' M', the table is tilted to the right, and when the carriage has been brought to the front of the machine over the table the handle M' is raised and the block is placed on the table, and then the handle M' is depressed, which action forces the teeth of the dog O' and the edge of the dog O into the block, as shown in Fig. 1, and then the operator pushes on the handles and forces the carriage, block, &c., back against the action of the revolving saw, as shown in Fig. 3, which results in sawing off a shingle from the bottom of the block, after which the carriage is again brought forward and the table tipped the other way, (which may be done by hand by the lever E,) so that the butt of the next shingle will lie to the left. Then the handle M' is again raised, which withdraws the teeth from the block and permits the latter to fall upon the inclined table, and then the handle M' is again brought down, not only forcing the teeth of its dog into the block, but also crowding the block against the knife-edge o, as before, and then the carriage and block are again pushed back, sawing off the shingle; and next the carriage is again brought forward, with the table tilted in the opposite

direction, and this is repeated until the block is reduced to a spalt; but, in place of the hand-lever E, we prefer generally to use our automatic tipping device. Referring to Fig. 2, (wherein the table is supposed to be tipped to the left,) with this device, by the backward pressure of the carriage, the sleeve of the rear right-hand corner rod N presses against the sleeve k² of the bent rod K² and forces said rod back against the action of the spring K', and this causes the pawl k³, which engages with one of the notches p in the outer rim of the cam P, to also move back, turning the said cam back the distance between two notches, whereby as the cam begins to turn to the right the upper friction-roller f is forced downward until that point of the trefoil depressions which was at the left of the said upper roller is directly on top, and then, as the lower roller f is freed from the point whereon it rested, that roller drops into the hollow next thereto, and thus the lever F is forced downward, which tilts the table in the opposite direction, or to the right. As soon as the carriage is drawn forward the spring K' forces the rod K² forward also, and its pawl k³ engages with the next notch p in the cam, which, as it begins to revolve, relieves the upper friction-roller f from pressure and raises the lower roller upon the next succeeding point, thereby restoring the parts to the position shown in Fig. 2 and automatically tipping the table again to the left. When the blocks have been sawed into shingles, there still remain portions of each block too thin to extend the distance between the dogs and the tipping table, and these portions are termed "spalts." Heretofore spalts have generally been waste products; but with our machine we are enabled to saw the entire spalt into shingles, and this we accomplish by means of our supplementary or spalt frame, which is secured in the position shown in Fig. 4, and then (the tipping table having been removed, as it is not used) the carriage is drawn forward, and the operator holds a spalt with one hand up against the under side of the timbers Q Q' Q³, and also against the inside edge of timber Q', (which extends down below the other timbers for this purpose,) while with the other hand he bears down upon the handle w, and thereby forces the dogs r r' into the spalt, and which holds it securely, although the said dogs penetrate but a very slight distance, inasmuch as they are forced into the spalt from opposite directions.

In order to saw the shingles from the spalt with the butts at alternate ends, the guides K of the carriage must be alternately lower on one side than on the other, and then level with each other, and this is accomplished by means of the segments I and the bell-crank levers H H' and their attachments, already described. The teeth of the segments are just the distance apart required for the butt of a shingle after the device has been adjusted, and hence it is necessary, in starting, with a spalt like that shown in section in Fig. 8, to have the pawl H³ on

one side in the first notch of the segment and the corresponding pawl, H^3 , on the other side of the machine in the second notch of the segment. Then, after the spalt has been pushed back 5 against the saw, and one shingle sawed off, and the carriage drawn forward again, the pawl that was in the first notch is moved to the second notch and the spalt again pushed back, the two pawls being each in the second notch 10 of their representative segments. The next adjustment is to advance the pawl that was originally in the second notch into the third notch, and the next adjustment (if the spalt requires so many) would be to bring the other 15 pawl into the third notch of its segment, and thus the opposite pawls would be alternately moved a notch at a time as long as a chip remained of the spalt, and the guides $K\ K$ would alternately be on a level with each other, and 20 then the thickness of a butt apart in height, as stated.

In sawing from the block the thickness of the butt of each shingle is regulated in this manner: When the leveling-bar B has been 25 adjusted to position, screw-bolts b^5 and b^6 are screwed up through the lugs B^5 and B^6 to the proper height, and there secured by their jam-nuts, as shown in Fig. 1, so that as the support C of the tipping table oscillates from 30 side to side the arms of the T -frame can only drop the distance allowed by these bolts b^5 and b^6 , and hence the thickness of the butt is thereby determined, while the spring B^3 and link C^4 guard against accidental displacement; but 35 in sawing from the spalt, as the tipping table and leveling-bar are not used, another method of adjustment becomes necessary, and we then regulate the thickness of the butt by raising or lowering the segments I by loosening 40 the jam-nut i^4 on the end of the bolt h' , and then turning the adjusting-screw i^2 , and then again tightening the nut i^4 against the collar i' , the degree of elevation of the segment thus 45 determining the thickness of the shingles as the teeth of the segment are brought nearer to or raised farther from the bolt h' , which is the pivotal axle of the bell-crank H' ; and to regulate the segments so as to enable the spalt-frame to lower sufficiently to saw the last 50 shingle held by the dogs $r\ r'$, the adjusting-screws i^3 are turned, which permits the required lateral adjustment of the segments I , and this is done, of course, before the jam-nut i^4 has been tightened to place.

55 In order to afford escape for the sawdust, the left-hand side of our auxiliary frame is made open from a point beginning near the attachment of the saw-guard Z on that side, and extending forward nearly to the rear bracket, 60 a^3 , and as the saw rapidly revolves all the dust flies out at this point, leaving the work perfectly clear.

Having thus described our invention, what we claim as new, and desire to secure by Letters Patent, is—

1. The combination, with a shingle-sawing machine, of a removable tipping table and a

spalt-carriage adapted, as described, to replace said tipping table when the latter is removed, substantially as set forth. 70

2. The combination, with a shingle-sawing machine, of holding-dogs constructed, substantially as described, so as to be capable of movement away from their operative position, and a spalt-carriage arranged to be 75 brought into operative position between said dogs when the dogs are moved out, substantially as set forth.

3. The combination, with a shingle-sawing machine, of a spalt-carriage provided with 80 mechanism, substantially as described, to hold the spalt from above, so that the ends and sides of the spalt may be clear.

4. The combination, with a shingle-sawing machine, of a spalt-carriage having supporting-bars, and dogs constructed, substantially 85 as described, to project below said bars and into the upper surface of the spalt.

5. In a shingle-sawing machine, a spalt-carriage composed of side timbers, as $Q\ Q$, end pieces connecting said side timbers, supporting-bars, as $Q^3\ Q^4$, connecting the end pieces, and arranged between the side timbers, and a series of dogs arranged between said bars $Q^3\ Q^4$, so as to engage with the upper surface of 95 a spalt, all combined substantially as stated. 90

6. The combination, with the frame of a spalt-carriage, of a pair of dog-bars having dogs arranged diagonally, as described, so as to project below the frame of the carriage, 100 and mechanism, substantially as stated, for giving said bars an oblique movement, all substantially as described.

7. In a machine for sawing shingles, the combination of a horizontal carriage with a 105 spalt-frame carrying movable bars, provided with downward-projecting dogs for supporting a spalt and carrying it against the saw, substantially as set forth.

8. In a sawing-machine, the combination of 110 a horizontal carriage, spalt-frame, movable head-blocks, connected to the guides of the carriage by bell-cranks, and pawls and segments for lowering either guide to change the inclination of the spalt-frame, substantially as 115 set forth.

9. The combination, with the timbers of the spalt-frame, of the dog-bars $R\ R'$, suspended therefrom, and carrying diagonal depending dogs $r\ r'$, the said bars being adapted to be 120 moved in opposite directions, substantially as set forth.

10. The combination of the spalt-frame, timbers $Q\ Q'\ Q^3\ Q^4$, transverse frames SS , dog-bars $R\ R'$, having end extensions, R^2 , with diagonal slots r^2 , central projections, R^3R^4 , with perforations r^3 and r^4 and diagonal dogs $r\ r'$, links T and U , standards V , arms W , and handle w , substantially as set forth. 125

11. In a shingle-machine, a spalt-frame 130 having dog-bars suspended therefrom, adapted to move in opposite directions, and provided with diagonally-depending dogs, pointing in opposite directions, in combination

with standards, links, and lever-arms connected to the upper portion of the spalt-frame and to the movable dog-bars, whereby a downward pressure on the said lever-arms will force 5 the dogs into a spalt held beneath and lock them in such position, substantially as set forth.

12. The combination of the guides K K and telescoping frame supported between them, 10 and the head-blocks, bell-cranks, and links supporting said guides, with the lever H², pawl H³, segments I, slotted for the reception of the bolt h', adjusting-screws i² i³, nut i⁴, collar i, and lugs i' and g, whereby the said

segment may be adjusted vertically to regulate 15 the thickness of the shingles sawed from the spalt, and also laterally to regulate the frame for the last shingle, substantially as set forth.

In testimony that we claim the foregoing we have hereunto set our hands, on this 30th day 20 of December, 1882, in the presence of two witnesses.

JOHN CHALLONER.
